192,939

COMPRESSION TESTER

Ivan L. Blowers, Plainwell, Mich., assignor to Kal-Equip Company, Otsego, Mich., a corporation of Michigan

Filed Mar. 8, 1960, Ser. No. 59,665

Term of patent 14 years

(Cl. D52—6)

FIG. 1.

FIG. 2.

FIG. 3.

FIGURE 1 is a perspective view of a compression tester, showing my new design;

FIGURE 2 is a side elevational view thereof; and
FIGURE 3 is a top plan view thereof.

I claim:

The ornamental design for a compression tester, as shown.

References Cited in the file of this patent

UNITED STATES PATENTS

2,500,395	Arden	Mar. 14, 1950
2,579,408	Ureeland	Dec. 18, 1951
2,823,542	Walraven	Feb. 18, 1958

FOREIGN PATENTS

252,601	Italy	-----	Mar. 28, 1927

OTHER REFERENCES

Universal compression tester, model 345A, on back cover page of Heyer "factory approved" equipment, recd. Jan. 26, 1959.

"Lanoke Compression Meters," model 118A, on page 7, recd. Feb. 2, 1944, Lanagan & Hoke, Inc., circular.

Nolands Industrial Supplies Catalog, © 1957, lower lefthand corner page T605, item No. C-404-S adapter.